UNITED STATES PATENT OFFICE.

HOWARD LACY, OF CARSHALTON, ENGLAND.

CONSTRUCTION OF ELECTROMAGNETS.

No. 928,136.

Specification of Letters Patent.

Patented July 13, 1909.

Application filed August 31, 1906. Serial No. 332,845.

To all whom it may concern:

Be it known that I, HOWARD LACY, a subject of the King of Great Britain, residing at Kelvin, Camden Road, Carshalton, in the county of Surrey, England, engineer, have invented certain new and useful Improvements in the Construction of Electromagnets, of which the following is a specification.

10 This invention has reference to the type of electromagnet which formed the subject matter of Letters Patent of Great Britain granted to Dugald Clerk, on a communication from myself, Louis F. Johnson and 15 Walter J. Slack, dated September 24th 1895, No. 17790 and is designed to rectify certain defects and omissions presented by the construction therein described, which defects were inimical in practice to the working of that invention.

Figure 1 shows by a plan view a pair of cores *a* with their yoke *b* and the four spreaders *c*, *c*, *c*, *c*, and their four diamagnetic plates *e*, *e*, *e*, *e*, the spreaders and plates 25 of the left leg of the core being in section. Fig. 2 shows a plan of a pair of helices wound upon the pair of cores shown by Fig. 1, with the one spreader and one plate *e* of the left leg in section. Fig. 3 is a back view of Fig. 1 and Fig. 2. Fig. 4 is a front view of Fig. 2 and Fig. 1. Fig. 5 shows diagrammatically a method of winding helices adapted for low voltages, and is a section of one leg of the magnet *d*, showing 30 the course taken by the wires *r*, *s*, *t*, in the left leg of the magnet, with the core *a* and interposed insulations *z*, *i*, *i*, et cetera. The 35 wire *r* is started right handed upon the one leg and the corresponding wire on the opposite leg is wound starting left handed. In Fig. 5 and in the left leg of the magnet Fig. 2 the ingoing ends of the wires *r*, *s*, *t*, are respectively marked 1, 3, 5, while the outgoing ends of these wires are respectively 40 marked 2, 4, 6. Fig. 6 is a plan in partial section of Fig. 5 and to the same scale.

The right leg of the magnet Fig. 2 is arranged with its gradations of wire in the same order as in the left leg of the magnet 45 but the windings are in the opposite direction.

As an approved construction designed to carry out my invention I would give the following formula for use in dealing with 50 commercial or lower voltages:—

The core, *a* is made of bunches of soft

wrought iron wires, cut into even lengths and clamped on the ends of the poles by spreaders *c* of twice the diameter of the bundle it is placed upon. This clamping should be done so firmly as to bring the spreaders *c* and the wires *a* at the ends into the closest possible contact. The spreaders or washers, *c* should also be of soft wrought iron, and the diameter outside should, as 60 already mentioned, be twice the diameter of the bundle of wrought iron wire on which the spreader is to be firmly clamped. This spreader is bored out centrally so that the bundle of wire passes clear through it and 65 when finished the ends of all the wires are flush with the front faces of these spreaders. The plates, *e*, *e*, to hold the helix of wires to be wound on this core may be made of brass, vulcanite or other suitable substance, 70 but preferably of a high electrical conducting or diamagnetic material aluminium being convenient; such plates being bored out centrally and slipped on the bundle of wires, or core *a* before clamping on the second 75 spreader *c* and these plates fit firmly against the back of the spreaders. The plates at the ends of the cores which will be the back end of the electromagnet have small holes *f*, *f*, bored through them and bushed or lined 80 with insulating material through which the ends 2, 4, 6, and commencements 1, 3, 5, of the various sized wires constituting the helix wound on the cores are brought out for purposes to be described later. These plates *e*, *e*, 85 when made of diamagnetic material aid in concentrating the lines of force around the spreaders.

The yoke, *b*, is a plate of soft wrought iron and the best effect generally is attained by 90 making it equal in size (in square inches) to one half the length of one of the cores and in width equal to the diameter of the spreaders. The thickness being given according to the necessary strength of material 95 required to safely sustain the total weight of the completed magnet and equivalent armature. This yoke *b* is placed on the spreaders *c*, *c*, at the back end of the cores *a* and is held against the same by studs *g*, screws, or like 100 connections, let into, or otherwise connecting the spreaders and the joint should be even and watertight.

In winding the helix: First carefully and thoroughly insulate the core *a* then wind the 105 spools of the magnet in layers, each layer of winding being carefully and effectively in-

sulated from the layer above and the layer below it in the construction, the size of winding wire I furthermore vary in thickness, forming the layers next adjacent to the core 5 of heavier wire than those superimposed thereon. The component wire forming each successive set of layers from the core to the circumference is of diminished thickness, and the thickness of wire of each set of layers 10 is graduated so as to bring in sufficient resistance at each change of grade of wire without producing any excessive retardation of current, the outermost layers being necessarily of the finest grade. The gradations 15 of thicknesses of wires are varied and adjusted to circumstances, the windings always increasing in number of layers as they decrease in diameter of component wire. The wires of the windings are reversed in the 20 direction of their winding at the end of every second layer, the direction of winding of two layers being arranged say, in the direction known as clockwise and the next two layers in the opposite or contra-clockwise direction 25 and so on alternately.

As a practical illustration of actual manufacture supposing direct current to be the source of electrical energy and dealing with the lower voltages I proceed as follows:—
 30 The core, *a*, is an assemblage of wrought iron wire of straight even lengths and formed into a round core. The spreaders, *c*, *c*, are two pieces of soft wrought iron each with a central hole and finished smooth on both 35 sides. The diamagnetic plates, *e*, *e*, finished on both sides have near the bottom of each at the back of the magnet a row of holes *f* to receive wires as hereafter explained. As many wires as possible are crowded within 40 a predetermined area by clamping them with heavy pressure near one end of the bundle and on this end is placed a spreader *c* heated and expanded, using such slight force as may be requisite. As soon as the spreader 45 has shrunk the clamp is removed and the rigid hold on the wires is then taken up by the spreader—the ends of wire extending $\frac{1}{2}$ to $\frac{1}{4}$ inch beyond it. The bundle *a* is now threaded through the hole in a plate *e*, arranging the best finished face of each plate 50 *e* in contact with the back of the spreader *c*. Now make up the other end of core, clamp it as before, apply the second plate *e*, the second spreader heated and then allowed to 55 cool and shrink and remove clamp, but with the use of hydraulic pressure the process is simplified. The surplus lengths of wires extending through the spreaders having been trimmed off flush leave a perfectly flat and 60 even surface at each end. The inside faces of these spreaders should be cleaned and each plate *e* set evenly against them.

The wires used in winding the helices hereafter referred to as Nos. 14, 16, 18 and 65 so on respectively are so designated to indi-

cate their relative diameters. They are each formed of double cotton covered copper magnet wire and the flexible cotton covered copper wire or the like ends say 12" long referred to as being soldered on at the beginning and ending of each size of wire, are carefully adjusted so that their carrying capacity is equivalent to the wire they are soldered to. The beginnings and endings of each size of wire after being brought or 70 passed through the holes at *f* are fastened to 75 prevent slipping of the windings.

It is essential to the success of this invention that before commencing to wind the second layer of wound wire the first layer 80 should be efficiently insulated as by the application of shellac and thick insulating paper, or other suitable insulating material, and thereafter each and every layer of wound wire must be similarly insulated 85 from each adjacent layer.

At each bending back of any given size of wire on itself to form a light strong string or the like binding tie is applied giving one or two turns close to the plate *e* to keep the 90 wire from slipping out of place upon the direction of wind being reversed.

After placing the core *a* (Fig. 5) in a lathe or the like and a plate *e* in close contact with each spreader *c* the core *a* is wrapped 95 tightly with insulating material covering the core wires *a* very carefully, commence to wind thereon wire *r*, say No. 14, having first affixed the flexible end 1 referred to, putting it through an end hole *f* 100 allowing enough flexible end inside plate *e* to go once around the core, wind on evenly and closely across to the other plate *e* and apply insulation *i*. The winding is now continued the latter still moving in the same 105 direction as when winding the first layer. Winding evenly and closely coming back to the starting point; now having laid two layers again apply insulation *i*. This wire *r* is cut off and the said flexible end soldered 110 on and the end 2 is passed out through a hole at *f* and fastened. Next take No. 16 wire (s Fig. 5) and solder on a flexible end 3 pass it through a hole *f*. Reverse the motion of the lathe, so that the winding proceeds in the opposite direction to what it was when winding on the first two layers, wind evenly and closely up to the plate *e* 115 and insulate at *i*, then continue winding back to point of commencement and again 120 insulate. Here bend the wire back on itself, fasten, reverse the motion of the lathe, and wind evenly to the end, and insulate; continue winding back to the point of commencement. Cut off wire, add flexible end 125 4 and pass it through hole at *f*. Take now No. 18 wire *t* add a flexible end 5 pass through hole at *f*, reverse the motion of the lathe to the direction it was last moving, and wind evenly to the end, insulate and 130

wind back to commencement, bend wire back on itself and fasten. Insulate last layer. Reverse motion of the lathe and wind evenly to the end, insulate and wind back to the point of commencement; again insulate. Bend wire back on itself and fasten. Reverse the motion of the lathe and wind evenly to the end, insulate and wind back to point of commencement. Cut off 5 wire and add flexible end 6 pass it through hole at *f* and fasten. Should it be desired to continue the winding of such a helix, as that just described, in order to increase its general efficiency, by further developing it, 10 using a finer gage of wire which would be No. 20 gage in this case, and the number of layers should be eight instead of six layers as in the preceding grade of wire and correspondingly if the efficiency is further enhanced by a further winding which would 15 be No. 22 in this case the number of coils will be increased to ten. The formula as to reversals of direction of winding and their relation to the prior winding and as to the 20 interspacing of insulation at each layer being strictly attended to.

As an alternative method of winding the helix so as to be better adapted for higher voltages than that just described I proceed 25 as follows:—Having prepared a core and applied the two first layers of coarsest winding *r* (as in the previous instance) I then bend the wire *r* back on itself and fasten. The motion of the lathe is now reversed, and 30 the winding evenly continued to the other end, again insulate at *i* and the winding is continued with the lathe in the same direction as for the last layer and insulated. This wire *r* is cut off and the said flexible 35 end soldered on and the end 2 is passed out through a hole at *f* and fastened. Next take 40 No. 16 wire, (s Fig. 5) and solder on a flexible end 3 pass it through a hole *f*, reverse the motion of the lathe, so that it revolves 45 in the same direction as when winding on the first two layers *r* wind evenly and closely up to the plate *e* and insulate at *i* then continue back to point of commencement and again insulate. Here bend the wire back, 50 on itself reverse the motion of the lathe, and wind evenly to the end and insulate; continue winding back to point of commencement. Here bend the wire back on itself fasten and insulate, reverse the lathe wind 55 evenly to the end; insulate and wind back evenly to point of commencement; cut off wire, add flexible end 4 and pass it through hole at *f*, and insulate. Take now No. 18 wire *t*, add a flexible end 5 pass through 60 hole at *f*, reverse the motion of the lathe to the direction it was last moving, and wind evenly to the end insulate and wind back to commencement. Bend wire back on itself and fasten. Insulate last layer. Reverse 65 motion of the lathe and wind evenly to the

end, insulate and wind back to the point of commencement; again insulate. Bend the wire back on itself and fasten. Reverse the motion of the lathe, wind evenly to the end, insulate and wind back to point of commencement, insulate and bend wire back on itself and fasten, reverse the motion of the lathe wind on evenly to the end, insulate again and wind back to point of commencement, cut off wire and add flexible end 6 70 pass it through hole at *f* and fasten. Now take No. 20 wire, solder on a flexible end as before and pass it through a hole at *f* and insulate; reverse motion of the lathe and wind on evenly to the end and insulate, wind 75 back to point of commencement. Bend wire back on itself fasten and insulate, reverse motion of lathe and wind on an even layer, insulate and wind back to the point of commencement, again insulate, bend wire back 80 on itself and fasten, reverse the lathe, wind on an even layer, insulate and wind back to point of commencement, insulate and fasten, reverse lathe and wind on evenly to the end, insulate, wind back to point of commencement, 85 insulate. Bend wire back on itself and fasten. Reverse lathe and wind on evenly to the end insulate, and now wind on evenly the last layer to the point of commencement. Cut off wire, add a “flexible 90 end,” pass same out through a hole at *f*, and securely fasten.

To further develop such a magnet for certain purposes, where such an efficiency might be called, using a finer gage of wire which 100 would be No. 22 gage in this case, and in number of layers added twelve as against ten layers in the preceding set, and otherwise strictly following the formula as to reversals, relative capacities of wires, interspacing of insulation at each layer, and so on.

The beginnings and endings of the various grades of wire I bring out of the end of the magnet so that various combinations may 110 be made as between the gages by which the current can be sent through all the wires successively or through two or more sizes jointly. By these means I can attain the following variations of combinations:—all 115 series, all multiple, series multiple, multiple series, multiple series multiple; shunt series, shunt multiple, shunt multiple series, shunt series multiple, and so on, the more various sized wires on the electromagnet the more 120 combinations and such other variations of combination as will be obvious to a skilled electrician. By these and similar combinations among other advantages facility for the adaptation of such magnet to variations 125 of current of electrical energy employed are obtainable.

The length of the yoke should be equal in measurement to half the length of one leg of the magnet divided by the diameter of the 130

spreader and the thickness should be proportioned in order to attain strength of the material necessary for the performance of the work for which the magnet is designed for 5 instance:—bundle of wire 1" spreader 2" length of wire or core 30". Yoke 7½" long.

Electromagnetic helices wound and constructed as hereinbefore described will be found useful for employment as the primaries 10 in induction coils, as well as for various other applications of the electromagnets.

Electro-magnets have been constructed in accordance with the present invention and used in connection with induction coils, 15 motors and other electrical apparatus, and such magnets have been found to possess the advantage of a material reduction in the cost of production, due to the reduced amount of wire and the decrease in the size of the magnet 20 in order to obtain given results, and the necessity of using a rheostat in connection with motors and similar apparatus is obviated, and in its stead may be employed a simple switch or controller for connecting 25 the several windings in different combinations. In this way the speed of the motor may be readily controlled and an economy 30 in current consumption as distinguished from magnets which require the use of a rheostat for introducing external resistance in the circuit, the excess of electrical energy being in those cases converted into heat and thus wasted.

Having now particularly described and 35 ascertained the nature of my said invention, and in what manner the same is to be performed, I declare that what I claim is:—

1. An electro magnet comprising a core, 40 groups of even numbers of layers of wire disposed thereon, the diameter of the wire composing each successive group diminishing progressively and the number of layers in each successive group increasing in direct arithmetical progression, and insulating material 45 between the core and its adjacent winding and between successive layers of the series, whereby the resistance of the winding increases in definite proportions through the electro magnet.

50 2. An electro magnet comprising a core,

windings composed of superimposed groups of even numbers of layers of wire disposed thereon, the diameter of the wire in each successive group decreasing progressively and the number of layers in each successive group increasing in direct arithmetical progression, the direction of the winding being reversed at the end of every second layer and all the layers being insulated from one another.

60 3. An electro magnet comprising a core, windings composed of superimposed groups of even numbers of insulated layers of wire disposed thereon, the diameter of the wire in each successive group decreasing progressively and the number of layers in each successive group increasing in direct arithmetical progression, the direction of the winding being reversed at the end of every 65 second layer and the free ends of the wire composing each group being brought out at the same end of the magnet for the purpose of being connected up in accordance with any desired combination, substantially as described.

75 4. An electro-magnet comprising a core, windings applied thereto, the wire composing said windings diminishing in size progressively in a direction from the core outwardly and increasing in the number of 80 layers in definite progressive order with each reduction in the size of the wire whereby the resistance of the windings will be increased in definite degrees from the core outwardly, the direction of the winding being reversed 85 at the end of every second layer and the beginnings and ends of each size of wire being exposed at the exterior of the magnet whereby such windings may be connected in different combinations, and an efficient 90 body of insulating material interposed between the layers of every winding.

In testimony whereof I have hereunto set my hand in presence of two subscribing witnesses.

HOWARD LACY.
